GARMENT FLAP FASTENER

Uriah G. Bumbarger, Cleveland, Ohio

Application April 2, 1934, Serial No. 718,649

5 Claims. (Cl. 2—78)

This invention relates to garment flap fasteners for application to various under garments, such as a single piece garment which is more often formed of knitted goods manufactured as a combination shirt and drawers; and which 5 piece is adapted to be formed with a vertical slot in the back, and having overlapping edges which latter normally remain overlapped in a suitable fit, but are adapted to be separated when the wearer desires, but can be drawn into the original 10 position when other clothes are to be manually closed, and the edges of the flaps are again overlapped. Difficulty has been encountered by former underwear of this character, because of inconvenience and discomfort in closing the flaps 15 and retaining them closed.

It is my purpose to accomplish the desired result by providing straps of unequal length and attaching one end of each strap together at one point and at a side of the garment, while the 20 opposite ends of the straps are secured to the respective flap edges which overlap to close the mentioned slot at the back of the garment. The common ends of the straps are provided with a button hole adapted to detachably fit a button 25 attached to the described point at the side of the garment. Such arrangement of the straps for closing said vertical slot when the strap ends are buttoned, may be accomplished readily, a practical embodiment of which in a unitary garment is represented in the accompanying drawing, in which,—

Figure 1 is a front elevation of a single piece garment and showing at one side a fastening button for detachably securing thereto my improved flap fastener;

Figure 2 is a rear elevation of the garment showing the overlapping flap in closed position over the vertical slot, and the flap edges having 40 one end of the fastener secure thereto externally of the garment, and the other end shown entering a slot opposite the other end of the fastener;

Figure 3 is a view similar to Fig. 2, but showing 45 the flaps separated and the fastener device unbuttoned;

Figure 4 is a cross section of the rear walls of the garment, taken through a plane indicated by the line 4—4 of Fig. 1; and showing the portions in closed position, and,

Figure 5 is a view similar to Fig. 4, but showing 50 the fastener parts in position when the flaps are separated.

The unitary body 5 of the undergarment has 55 the usual front detachable seam 6, as chosen for

illustration of my flap fastener applied thereto.

Any garment having a seat seam such as is adapted to be closed by drawing the outer flap 9 over the under flap 10, as shown in Figs. 2, 3, and 4 of the drawing, is suited to very effective 5 operation for the purpose intended by my invention. While I have shown the garment as one having short arms 8 and usual legs 7, my flap fastener is not exclusively fitted to such a one-piece garment, but may be used with advantage 10 on any garments having the vertical seat seam, as above stated.

Assuming the garment shown in rear view in Figs. 2 and 3, and the outer flap 9 closed over the under flap 10, a reinforce patch 11 will best be 15 secured external of the goods on the right hand side of the wearer, and a button 20 provided at this point, as shown in Figs. 1, 3 and 5, for detachable fastening of the loose end of the straps 12 and 15 which are united at 14 and provide a 20 button-hole there for suitable fastening on the button 20. The strap 12 is the shorter, and is wider than the longer strap 15. Further, this wider strap is permanently secured at the seam 13 to the outer edge of the flap 9, and thereby is 25 adapted to exert great pulling force on the flap 9, in drawing the flap 9 to closed position before buttoning the united portion 14 on the button 20.

Tracing the strap 15 back from the point 14, it passes inwardly through the reinforced slot 30 16 which is designed to lead through the outer flap 9 and through the reinforce piece 18 shown clearly in Figs. 2, 3, 4, and 5. The extreme end of the strap 15 is secured at 17 by seam to the inner edge of the inner flap 10, so that outer 35 pulling force exerted at the point of attachment 14 will tend to draw the flap 10 to the inner position shown in either view in Figs. 2 or 4. The closing operation of the flaps 9 and 10 may 40 be accomplished by drawing the unitary attachment 14 toward the button 20, thereby pulling the connection 17 beneath the reinforced slot 16.

All the views of the drawing, except Fig. 1, clearly show that outer pressure exerted against the longer strap 15, and which can be done by 45 the wearer, tends to draw the flap 10 from its position in Fig. 4 to that in Fig. 5, while the strap is drawn through the reinforced slot 16 until the unbuttoned end 14 reaches said slot, the seams 11 and 13 at the edges of the flaps being separated from the position of Fig. 4 to that shown in Figs. 5 and 3. It will now be clear that a positive slack 19 will exist in the longer strap 15 which, by raising somewhat above its position in Fig. 3, 50 will conveniently permit separation of the flaps 55

temporarily; but when the wearer rises to approximate erect position, and the flap edges loosely closed, may be held in such closed relation by grasping the united ends at 14, and taking up such slack by repositioning the buttonhole slot at 14 in engaged position on the button 20, as shown in either Fig. 2 or 4.

The opening and closing positions of the parts 9, 10, 12, 14, 15, 16, and 20 are shown well in the last four views of the drawing. The movement of such parts in the changes from one position to the other, obviously requires a sliding movement of the strap 15 through the reinforced slot 16 remote from the outer edge of the flap 9. This is controlled by the wearer by manually grasping the parts at 14 and 19, and applying the stronger force at one or the other of the latter parts, and button or unbutton the part 14 at 20.

The garment is shown flattened out in the first three views, the straps 12 and 15 ordinarily being designed to press slightly upon the buttocks of the wearer, when the flaps are being closed and the garment is worn. It is of much importance also, the fact that no buttons or other hard engaging objects such as buttons, pins or hooks, need be used on my device, in a position to be sat upon when the flaps are closed. The only fastener for my garment at the seat seam is the button 20 at the side.

The manipulation of the improved flap fasteners which constitutes my invention, is readily accomplished in the following manner:—The outer flap 9 is held normally closed over the under flap 10 as shown from the rear in Fig. 2, and in section in Fig. 4. The connection of the outer ends of the straps 12 and 15 being then buttoned over the button 20, as shown in Figs. 2 and 4, in which the position of both the fasteners and the seam flaps is both comfortable and secure. When the wearer desires to seat, as at toilet, the unit 14 is easily unbuttoned from the button 20, the longer strap 15 as shown at Fig. 2, is drawn backwardly and upwardly sufficient to provide slack as at 19, in Figs. 3 and 5, this longer strap 15 being drawn through the slot 16 until said slack 19 is adequate, at the same time separating the flaps 9 and 10, as shown in Fig. 3, thereby opening the seam which can be done readily while the garment is loosened from the front.

When the said seam is to be closed, the wearer may reach the hands to the position for grasping the common connecting point at 14, as in Fig. 5, at the same time applying a pulling force to the straps which will draw the strap 15 outwardly through the slot 16, and at the same time pull the strap 12 over into overlapping position, and such attachment 14 forward to be secured on the button 20 at the side. This operation can be performed without opening the front seam 6, though it can be loosened if desired. While I have shown in much detail the application of my flap fastener to a single-piece undergarment, I do not however, desire to limit myself to the particular application of the fastener to any one garment having the vertical seam at the back, for I have found such application easily adaptable to garments of all kinds having the separable flaps as shown in Figs. 2 and 3.

Having thus fully described my invention what I claim as new and desire to secure by Letters Patent is:—

1. In a garment having an opening, flaps for covering the opening, and a fastener for detachably securing the flaps in overlapped position, comprising strap members of unequal length se-

cured together at one end to form an unitary attachment having a common buttonhole for engaging a button fixed on a side of the garment, the opposite ends of such strap members being attached to the edges of the respective flaps, the outer flap having an opening therein at a point remote from its edge, to receive the longer strap outwardly therethrough, so that engagement of the said button by the said common buttonhole in said attachment will tend to overlap the said 10 flaps.

2. In a garment having a seam, flaps for closing the seam and a fastener for detachably securing the flaps in overlapped position, comprising strap members of unequal length having one end of each attached to the edges of the respective flaps, the outer flap having an open slot therein at a point remote from its edge, to receive the longer of said strap members outwardly therethrough, the other ends of said members being united for a common manual application of pulling force to said united ends to draw the flaps into overlapping relation for closing the said seam, and means provided on the side of the garment for detachably receiving the common 25 united point of said strap members to hold the said flaps overlapped.

3. In a garment having a seam, flaps for closing the seam, and a fastener for detachably securing the flaps in overlapped relation, comprising strap members of unequal length secured together at one end in superposed position and having a common buttonhole therethrough, a button being fixed on a side of the garment on a line transverse of said garment seam, the other ends of said straps being secured to the edges of the respective flaps, the shorter of the strap members being broader and engaging the outer flap, there being a slot in the latter at a point remote from its edge to receive the longer and 40 narrower member therethrough loosely, so that engaging said buttonhole in said secured ends of the strap members on said button will overlap said seam flaps, while separation of the flaps when the strap members are detached from the 45 button, will loosen the longer strap member by movement through said slot in the outer seam flap.

4. In a garment having a seam, flaps for closing the seam and fastening means comprising, 50 for detachably securing said flaps in overlapping position, strap members of unequal length, secured at one end of each to the edges of said flaps respectively, and the opposite ends of said members united together so that a pulling force 55 applied to said point of union will exert an overlapping tendency to the flaps to which the strap members are secured, the said strap members being superposed in their securing position upon said flaps, the outer strap being the narrower 60 and extending inwardly through an opening in said outer flap at a point remote from its edge, so that the latter flap may engage the edge of the inner flap whereby a pulling force exerted on said point of union toward the fixed point established on the garment remote from the said flaps, will close said flaps in superposed relation with a resulting balanced strain on the two strap members.

5. In a garment having a seam, flaps for closing the seam in overlapped relation, and a fastener comprising strap members of unequal length and width secured together at one end, and having a buttonhole through the superposed union of said members, a button being fixed on a side 75

of the garment nearest the edge of the outer flap when overlapped, the shorter strap member having its opposite end attached to the outer flap edge of the garment seam, the outer flap having an opening therethrough remote from its edge to permit the longer strap member to pass through

said opening and secure its opposite end to the inner flap edge and engagement of said button by the buttonhole in the straps tending to detachably close the said flaps, whereby to close said seam.

URIAH G. BUMBARGER.
